CLAIM

The ornamental design for a selectively sealable evacuable storage bag, as shown and described.

DESCRIPTION

FIG. 1 is a top plan view of an embodiment of a selectively sealable evacuable storage bag;

FIG. 2 is a top plan view of a second embodiment of a selectively sealable evacuable storage bag;

FIG. 3 is a bottom plan view of the embodiment of FIG. 1; and,

FIG. 4 is a bottom plan view of the embodiment of FIG. 2. The broken line showing of the semi-automatic pistol forms no part of the claimed design.

1 Claim, 2 Drawing Sheets(56)
